CLAIM

The ornamental design for a hoodie, as shown and described.

DESCRIPTION

FIG. 1 is a left-side front perspective view of a first embodiment of a hoodie in accordance with the present invention; FIG. 2 is an elevational front view of the hoodie of FIG. 1; FIG. 3 is an elevational left-side view of the hoodie of FIG. 1; FIG. 4 is a top plan view of the hoodie of FIG. 1 with the right and left sides extended outward; FIG. 5 is a bottom plan view of the hoodie of FIG. 1 with the right and left sides extended outward; FIG. 6 is a left-side front perspective view of a second embodiment of a hoodie in accordance with the present invention; FIG. 7 is an elevational front view of the hoodie of FIG. 6; FIG. 8 is an elevational left-side view of the hoodie of FIG. 6; FIG. 9 is a top plan view of the hoodie of FIG. 6 with the right and left sides extended outward; and, FIG. 10 is a bottom plan view of the hoodie of FIG. 6 with the right and left sides extended outward. The broken lines showing stitching depict portions of the hoodie that form no part of the claimed design.
